US00D608365S

(12) **United States Design Patent**
Walsh et al.

(10) **Patent No.:** US D608,365 S
(45) **Date of Patent:** ** Jan. 19, 2010

(54) **USER INTERFACE FOR A PORTION OF A DISPLAY SCREEN**

(75) Inventors: **Daniel Walsh**, San Francisco, CA (US); **Amy Poling**, San Jose, CA (US)

(73) Assignee: **Adobe Systems Incorporated**, San Jose, CA (US)

(**) Term: **14 Years**

(21) Appl. No.: **29/318,435**

(22) Filed: **May 20, 2008**

(51) **LOC (9) Cl.** 32-00

(52) **U.S. Cl.** D14/485

(58) **Field of Classification Search** D14/485-495; D18/24-33; D19/6, 52; D20/11; D21/324-333; 715/700-867, 973-977; 345/757, 782, 848, 345/852, 850, 809, 837, 798, 752, 163, 156, 345/537, 474, 836, 419, 649, 656, 659, 426, 345/427, 582, 428, 440, 660, 634, 902, 418, 345/629, 700, 744, 747, 473; 705/10, 5; 709/223

(57) **CLAIM**

The ornamental design for a user interface for a portion of a display screen, as shown and described.

DESCRIPTION

A portion of the disclosure of this patent document contains material that is subject to copyright protection. The copyright owner has no objection to the facsimile reproduction by anyone of the patent document or the patent disclosure, as it appears in the Patent and Trademark Office patent files or records, but otherwise reserves all copyright rights whatsoever. The following notice applies to the software and data as described below and in the drawings that form a part of this document: Copyright 2008 Adobe Systems Incorporated. All Rights Reserved.

FIG. 1 is a front view of a user interface for a portion of a display screen, according to a first example embodiment of our new design; and,

FIG. 2 is a front view of a user interface for a portion of a display screen, according to a second example embodiment of our new design.

The broken line drawing of a portion of a display screen is environmental and is not claimed. All other broken line matter is not claimed.
